UNITED STATES PATENT OFFICE

2,514,238

MECHANICAL WALLPAPER PASTER

Charles W. Hesson, Louisville, Ky.

Application June 12, 1947, Serial No. 754,239

3 Claims. (Cl. 91—14)

1

This invention relates to a mechanical wall paper pasting machine.

It is an object of the present invention to provide a wall paper pasting machine adapted to support a roll of wall paper and to direct the same through a paste compartment and over a roller adapted to pick up paste and deposit it on the under side of the wall paper as it is pulled thereover and wherein while the paper is being extended, cutting the sides of the paper to the exact connection to trim it.

It is another object of the present invention to provide in a wall paper pasting machine, in addition to the roller arrangement for applying paste to the wall paper sheet, additional roll means within the same compartment adapted to be used for depositing paste upon the border strip which may be extended therethrough.

It is another object of the present invention to provide in a wall paper pasting machine, a paste roll which has a rubber sleeve surface adapted to pick up paste and adapted to be elongated so that the ends of the roll can be extended by stretching the rubber sleeve to adapt the machine for different width wall paper and wherein the cutting knives may likewise be adjusted to trim the different width wall paper sheets.

Other objects of the present invention are to provide a wall paper pasting machine which is of simple construction, inexpensive to manufacture and efficient in operation.

For other objects and for a better understanding of the invention, reference may be had to the following detailed construction taken in connection with the accompanying drawing, in which:

Fig. 1 is a front elevational view of my wall paper pasting machine.

Fig. 2 is a fragmentary and sectional view taken through the cutting knife device.

Fig. 3 is an end sectional view taken on line 3—3 of Fig. 2.

Fig. 4 is a side elevational view of my wall paper pasting machine with the paper extended through it.

Fig. 5 is a transverse cross-sectional view taken on line 5—5 of Fig. 1.

Fig. 6 is a fragmentary cross-sectional view taken on line 6—6 of Fig. 4.

Fig. 7 is a fragmentary cross-sectional view taken through one end of the paste applying roller and as viewed on line 7—7 of Fig. 5.

Fig. 8 is a fragmentary top plan view looking upon the top roller.

Referring now to the figures, 15 represents a tank having paste 16 therewithin. This tank is

2

supported above a door by adjustable legs 17 disposed at opposite sides and ends of the tank. One set of legs supports a wall paper roll 18 from which paper is drawn and extended over the front corner of the tank as indicated at 19 and through rolls 20 and 21 having cutting discs 22 and 23 uniting to trim the sides of the paper. Within the tank is a large roll 24 adapted to pick up paste 16 to deposit the same upon the under side of the paper as it is extended over the roll and between the roll 24 and a small roll 25. From the small roll 25, the paper is drawn over a top plate 26 which is pivoted at 27 so that it may be tilted upwardly as shown in Fig. 5 to provide access to the end of the plate 26 so that the paper can be severed therefrom conveniently. The edge of the plate 26 is indicated at 27 and the paper can be severed along this edge. The paper can be extended over a table top 28 prior to being placed upon the wall. Trim 29 from the cutting knives 22 and 23 will drop to the floor.

Roll 18 of the wall paper is supported on a shaft 31 and is retained against axial displacement thereon by set collars 32. The ends of the shafts are placed in brackets 33 on the legs 17.

Legs 17 are adjustable through brackets 34 on the sides of the tank 15 and are retained in their adjusted position by a set screw 35.

On the side of the tank 15 is a measuring device 36 which is operated by engagement of a pinion wheel 37 engaging with the paste applying roller 24. Measured quantities of the paper can accordingly be rolled off.

The paste applying drum 24 is formed of cup-shaped members 38 at the opposite ends of the same and a rubber exterior sleeve 39 connected to the members by clamping plates 41 on the end faces of the members 38. The end members are secured at their centers to an adjustable fitting 42, Fig. 7, threadedly connected to screw 43 and adjustable thereover to bring the cup-shaped members either closer together or farther apart whereby to stretch the rubber sleeve 39 as in the latter case to provide a longer paste roll 24. Lock nuts 44 can be adjusted to fix the fitting 42 in its adjusted position. The rubber sleeve 39 will provide a good surface on which the paste may be collected for deposit on the paper.

The tank 15 is of sufficient width to accommodate a second paste applying roll 45 over which border paper is extended. A top roll 46 engages with the paper to retain it upon the paste-applying roll 45. The tank has a partition 47 for supporting the inner ends of these rolls,

as well as the inner ends of the rolls 24 and 25. The border paper can be placed on the shaft 31 in the same manner that the roll 18 is placed thereon and to one side of the roll 18.

The rotating knife 23 is adjustable upon a threaded shaft 48 and the rotating knife 22 will be pressed toward the knife 23 by a spring 49 reacting between the knife 22 and the end of the roll 30. Knife 22 is on a square shaft 51. The shafts 48 and 51 are supported on a bracket 52 which is connected to the front of the tank 15. The shafts are connected together to drive one another by meshed gears 53 and 54. A bracket 55 extends upwardly from the shaft 48 to support the plate 26. The brackets 55 will pivot on the shaft 48 so that the plate 26 can be pivoted upwardly as shown in Fig. 5.

While various changes may be made in the detail construction, it shall be understood that such changes shall be within the spirit and scope of the present invention as defined by the appended claims.

I claim:

1. A wall paper pasting machine comprising a tank adapted to contain paste, a shaft in the tank, a paste-applying roll on the shaft and adapted to pick up paste and deliver it to an elevated position, said roll comprising a pair of cup-shaped members on said shaft at the opposite ends of said shaft, an elastic sleeve about said shaft, means on said cup-shaped members for securing the opposite ends of said sleeve to said members, adjustable fittings for said cup-shaped members at the center thereof, means on said shaft coating with said fittings for varying the length of said sleeve, rollers adapted to guide the extended wall paper over the paste-applying roll, certain of said rolls being arranged in pairs, and knife means associated with said pair of rollers to cut from the paper a trim slice.

2. A wall paper pasting machine comprising a tank adapted to contain paste, a paste-applying

roll pivotally connected to the tank and adapted to elevate paste to a location where it may be applied to the wall paper being extended thereover, roll means for extending the paper over the paste-applying roll, said paste-applying roll comprising a shaft, cup shaped end members adjustable on the shaft, an elastic sleeve extending between the end members and adapted to be stretched to provide paste-applying roll which may be adjusted for different widths of paper.

3. A wall paper pasting machine comprising a tank adapted to contain paste, a shaft in said tank, a paste-applying elastic sleeve in said tank on said shaft and adapted to elevate paste to an elevated position for application to paper which may be drawn over the paste-applying roll, means on said shaft connected to said sleeve adapted to extend the same along said shaft, a guide roll above the paste-applying roll over which the paper is extended, a bracket on the tank, a supporting shaft on said bracket, a plate pivoted on the supporting shaft and extending from the same toward and adjacent to the roll above the paste-applying roll to receive the paper therefrom, said plate being tiltable to an elevated position above the roll and having an edge over which the paper may be severed.

CHARLES W. HESSON.
